(57) **CLAIM**

The ornamental design for a tip for a ground engaging
machine implement, as shown and described.

DESCRIPTION

FIG. 1 is a front perspective view of a tip for a ground
engaging machine implement showing our new design;
FIG. 2 is a front view thereof;
FIG. 3 is a front view thereof with the front elevated;
FIG. 4 is a left side view thereof;
FIG. 5 is a rear view thereof;
FIG. 6 is a right side view thereof;
FIG. 7 is a top view thereof;
FIG. 8 is a bottom view thereof; and,
FIG. 9 is a rear perspective view thereof.
The broken lines illustrate structure or features that form no
part of the claimed design.

1 Claim, 5 Drawing Sheets
